UNITED STATES PATENT OFFICE.

MAXIMILIAN GALLEY, OF HANOVER, GERMANY.

FACE-PROTECTOR.

SPECIFICATION forming part of Letters Patent No. 704,311, dated July 8, 1902.

Application filed November 28, 1900. Serial No. 37,968. (No model.)

To all whom it may concern:

Be it known that I, MAXIMILIAN GALLEY, a subject of the German Emperor, and a resident of Hanover, Germany, have invented certain new and useful Improvements in Face-Protectors for Use During the Operation of Hair-Cutting, of which the following is a specification.

The object of my present invention is to provide a simple but efficient device for protecting a person's face while having his hair cut or dressed, so as to prevent the cut hair, &c., from dropping on his face.

The invention consists of the novel combination of parts fully described and claimed hereinafter.

In the accompanying drawings I have illustrated my invention with various means for holding the protector on a person's face.

Figure 1 is a side elevation showing my protector in its simplest form. Fig. 2 is a like elevation showing the protector with a mustache guard or band and attached to the ears of the wearer. Fig. 3 shows said protector with a chin-band as well as ear-bands. Fig. 4 shows the protector provided with a tray for collecting debris, and Fig. 5 is a general view of the device with the screen in section.

Referring to the drawings, *a* represents a curved screen made of transparent or translucent material, such as celluloid, gelatin paper, waxed linen, glass, &c., or of opaque material, such as sheet metal, paper, cardboard, &c. The upper edge of said screen is adapted to snugly fit around a person's forehead for the purpose of efficiently preventing anything from passing between the screen and the forehead upon the face of the wearer. The screen or protector extends from the forehead down sufficiently far to entirely cover and protect the nose and mouth as well as the eyes, reaching nearly or quite to the point of the chin. Attached to the upper edge of the screen *a* is a band *b*, which may be turned around the wearer's head and tied at the rear thereof, as shown in Fig. 1, or said band may have elastic ends *b'*, Figs. 2 and 3, attached to the said side edges of the screen *a* and adapted to be fitted around the ears of the wearer for the purpose of holding the device in position.

In order to hold the screen *a* away from the wearer's face, the inner side thereof may be

provided with a cushion or pad *c*, adapted to rest on the wearer's nose, or to the band *b* may be attached two side bands *d d*, adapted to be turned and tied under the wearer's chin, Fig. 1. The side edges of the screen *a* may be also attached to a closed elastic band *e*, adapted to fit around the wearer's chin.

The device may be further provided with an inner band *g*, adapted to fit over and hold the wearer's mustache, to fix or set the ends thereof.

In order to prevent the face-screen from slipping down, the same may be attached to the wearer's forehead by means of any suitable plaster fixed to the upper edge of the screen.

The device may further be provided with an open channel or tray *h* at its lower edge for collecting scurf, hair, and the like, as shown in Fig. 4. This as well as the mustache-guard may obviously be applied to any form of screen extending sufficiently far down from the forehead to practically shield the whole face.

When the screen is composed of transparent material, which is the preferable form, it is evident that the wearer's vision is totally unobstructed, and he can see all that passes around him with the same facility as if it were removed.

Having fully described my invention, what I claim, and desire to secure by Letters Patent, is—

1. A face-protector comprising a suitable curved imperforate screen adapted to fit around the wearer's forehead and cover his face to a point below the mouth, means for holding the screen in place, and means for holding the screen away from the wearer's face, substantially as set forth.

2. A face-protector comprising a suitably curved imperforate screen adapted to fit around the wearer's forehead and cover his face to a point below the mouth, a band attached to the upper edge of the screen and adapted to fit upon some part of the wearer's head to secure said screen in place, and means for holding the screen away from the wearer's face, substantially as set forth.

3. A face-protector comprising a suitably curved imperforate screen adapted to fit around the wearer's forehead and cover his

- face to a point below the mouth, a band attached to the upper edge of the screen and adapted to fit upon some part of the wearer's head to hold said screen thereto, and a suitable pad on the inner side of the screen and adapted to rest on the wearer's nose, substantially as set forth.
4. A face-protector comprising a suitably curved screen adapted to fit around the wearer's forehead and cover his face to a point below the mouth, a band attached to the upper part of the screen and adapted to fit upon some part of the wearer's head to hold the screen thereto, and an elastic band connected to the sides of said screen and adapted to fit under the wearer's chin, substantially as set forth.
5. The combination with a suitably-curved screen adapted to fit around the wearer's forehead and cover his face, and means for holding said screen in position on the wearer, of an inner band attached to the sides of the screen and adapted to fit over the wearer's mustache, substantially as set forth.
6. A face-protector comprising a suitably-curved screen adapted to fit around the wearer's forehead and cover his face, means for holding the screen in position on the wearer,

and an open tray projecting from the lower edge of the screen, into which the scurf, cut hair and the like may fall, substantially as set forth.

7. A face-protector comprising a suitably-curved screen adapted to fit around the wearer's forehead and cover his face to a point below the mouth, means for holding the screen in position on the wearer, a pad attached to the screen and adapted to sit on the wearer's nose, an inner band attached to the side of the screen and adapted to fit over the wearer's mustache, and an open tray projecting from the lower edge of the screen to receive chippings and other debris, substantially as set forth.

8. A face-protector comprising a suitably-curved screen of transparent material, adapted to fit over the wearer's forehead and cover his face to a point below the mouth, and means for attaching said screen to the head, substantially as set forth.

In testimony whereof I have hereunto set my hand in presence of two witnesses.

MAX. GALLEY.
